UNITED STATES PATENT OFFICE.

FREDERICK D. KENYON, OF MINNEAPOLIS, MINNESOTA, ASSIGNOR OF ONE-HALF TO
HARRIET R. ROOT, OF HENNEPIN COUNTY, MINNESOTA.

FURNACE ATTACHMENT.

Application filed December 20, 1926. Serial No. 155,907.

My invention relates to furnace attachments and an object is to provide means for securing more perfect combustion of coal or similar fuel than is possible in furnaces commonly in use. In furnaces which are in extensive use at the present time, only imperfect combustion of the fuel is obtained and a considerable percentage of the gaseous products from the fuel passes out of the furnace in an unconsumed condition. The result of this is that a large amount of potential heat is not utilized and quantities of smoke and soot are discharged into the atmosphere with resultant injurious effects. In carrying out my invention, I provide an attachment which may be readily applied to various types and sizes of furnaces and by means of which air is delivered above the burning fuel for mixing with the gas rising therefrom without obstructing the firepot with an air pipe or similar device passing therethrough.

The full objects and advantages of my invention will appear in connection with the detailed description thereof, and the novel features of my inventive idea will be particularly pointed out in the claim.

In the accompanying drawings which illustrate one form in which my invention may be embodied,—

Fig. 1 is a sectional elevational view of a furnace with my invention applied thereto, the section being a central vertical one. Fig. 2 is a sectional elevational view, the section being a central vertical one at right angles to that of Fig. 1 and an air distributor being shown in its operative position. Fig. 3 is a fragmentary sectional view corresponding to a portion of Fig. 2 and showing the air distributor in its retracted position. Fig. 4 is a view in vertical section on the line 4—4 of Fig. 1. Fig. 5 is a view in vertical section on the line 5—5 of Fig. 3, and on an enlarged scale.

Referring to the particular construction shown in the drawings, the numeral 10 designates the outer wall of a well-known form of furnace having a charging door 12, an ashpit door 14, grate bars 16, hot air pipes 18, a smoke-flue 20, and a firepot 22. Arranged outside of the furnace in any convenient position preferably at one side of the charging door and below the same, there is a blower 24 driven in any suitable manner as by an electric motor 26. The blower has a discharge pipe 28 which extends into the ashpit for de-

livering air thereinto for passage up between the grate bars and through the fuel placed thereon. Extending up from the pipe 28 outside of the furnace, there is a branch pipe 30 which is preferably in the form of a flexible conduit as shown. At the entrance into this branch pipe, there is a deflector 32 which serves to deflect a portion of the air delivered from the blower up into the branch pipe. Just above the entrance into the branch pipe, there is a perforated plug 34, the perforation in which may be varied in size according to the character of the furnace and the conditions under which the furnace is to be used so that the amount of air passing through the branch pipe may be reduced as considered desirable. The charging door is provided with an opening through which a sleeve 36 extends, this sleeve being held to the door so as to extend inwardly by a circumferential flange 38 bolted to the outside of the door.

Slidably mounted in the sleeve 36, there is a tube 40 which at its inner end has a downwardly turned member 42 which is closed except for a row of circumferential perforations 44. The tube 40 in connection with its perforated end member in effect constitutes an air distributor which sprays air upon the top of the fuel in the fire pot. The tube 40 on its upper and lower sides is provided with longitudinal ribs 46 and 48 as will be understood from Figs. 3 and 5. The outer end of the tube 40 is provided with a handle 50 having a grasping member 52 at its outer end and a ring 54 at its inner end. A set screw 56 passing through the ring 54 and engaged with the tube 40 prevents the handle from being pulled off. The ring 54 is further provided with grooves into which the aforesaid ribs 46 and 48 fit. The sleeve 36 is provided with similar grooves into which the ribs fit slidably. It will now be understood that the ribs 46 and 48 have a four-fold function.

They prevent the handle from turning on the tube 40, they prevent the tube 40 from turning in the sleeve 36, they serve as guides which fit slidably in grooves in the sleeve 36 so that the air distributor may be slid between the positions shown in Figs. 2 and 3 and finally, they serve to reinforce the tube 40 and prevent it from warping upwardly or downwardly under the influence of expansion and contraction. It will be understood that the air distributor is drawn back into retracted position as shown in Fig. 3 when the charg-

ing door is to be opened so as not to interfere with the free opening thereof. The delivery end of the branch pipe 30 is provided with an elbow 58, the outer end of which is secured thereto by a set screw 60 as shown in Fig. 1 and the inner end of which is adapted to fit snugly but slidably into the outer end of the tube 40 as will be understood from Fig. 2 so that the pipe 30 may be detached from the tube 40 when the charging door is opened. When thus detached, a chain 60 secured at one end to the frame of the door 12 and secured at the other end to the pipe 30 prevents the latter from dropping down upon the floor.

15 The operation and advantages of my invention have to a large extent already been set forth. The air which passes through the pipe 28 into the ashpit increases the draft. The air passing through the branch pipe 30 and through the air distributor is sprayed upon the top of the burning coal and tends to completely oxidize the gas as it rises from the burning fuel. In this manner almost complete combustion is secured, thereby con-

serving fuel and preventing the accumulation 25 of soot and discharge of black smoke. The tube 40 may be made standard length sufficient for installation in large furnaces and it is a comparatively simple matter to cut off the outer end of the tube for adapting the 30 tube to be installed in smaller furnaces. The attachment may, therefore, be readily applied to various sizes and types of furnaces.

I claim:

A furnace attachment comprising a blower, 35 a guide sleeve secured to the inner side of the charging door of the furnace, an air distributor tube slidably mounted in said sleeve, a flexible conduit leading from said blower, a detachable connection for attaching said conduit to the outer end of said tube, a ring detachably secured around the outer end of said tube, and a handle member connected with said ring.

In testimony whereof I hereunto affix my 45 signature.

FREDERICK D. KENYON.
